UNITED STATES PATENT OFFICE.

ISABEL CLAFLIN LASIER, OF HOLLISTON, MASSACHUSETTS.

DESIGN FOR A MIDDY-BLOUSE.

55,950.

Specification for Design.

Patented Aug. 3, 1920.

Application filed April 26, 1920. Serial No. 376,878. Term of patent 7 years.

To all whom it may concern:

Be it known that I, ISABEL CLAFLIN LASIER, a citizen of the United States, residing at Holliston, in the county of Middlesex and State of Massachusetts, have invented a new, original, and ornamental Design for Middy-Blouses, of which the following is a specification, reference being had to the accompanying drawing, forming part hereof.

Fig. 2 is a back view.

I claim:

The ornamental design for a middy blouse as shown.

ISABEL CLAFLIN LASIER.
